UNITED STATES PATENT OFFICE.

PETER ZAKIT, OF AKRON, OHIO.

MINE-CATCHER.

1,138,525.

Specification of Letters Patent.

Patented May 4, 1915.

Application filed February 10, 1915. Serial No. 7,421.

To all whom it may concern:

Be it known that I, PETER ZAKIT, a citizen of the United States, residing at Akron, in the county of Summit and State of Ohio, have invented certain new and useful Improvements in Mine-Catchers; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to certain new and useful improvements in mine catcher attachments for vessels and it has for its object the provision of a practical attachment of this character by the use of which explosive mines may be caught and transferred to the deck of a vessel without the danger of explosion by contact.

20 To these ends and to such others as the invention may pertain, the same consists in the novel features of construction and peculiar arrangement, and adaptation of parts, all as will be more fully hereinafter described, shown in the accompanying drawings and then specifically defined in the appended claim.

25 My invention is illustrated in the accompanying drawings, in which:

Figure 1 is a side elevation of the bow of a vessel provided with my mine catcher, and Fig. 2 is a top plan view.

30 Reference now being had to the details of the drawings, 1 represents the bow of a vessel, 2 the mine catcher or drag which is carried by the free ends of pivoted bracket members 3, which members are pivoted upon opposite sides of the bow portion of the vessel, as shown at 4. The free ends of the said bifurcated members 3 are connected with the outer upper and lower corners of the frame 2. The body portion of said drag or catching device consists of vertically and horizontally extended ropes 5 and 6. The rod or member 7, which comprises the lower

end of the drag, is provided at intervals of its length with horizontally extended hooks 50 8, 8.

9 is a cable or rope connected at one of its ends with an eye 10 at the apex of the frame 2, one arm of which extends upon opposite sides of the vessel as indicated in Fig. 2. Said cable is extended over a suitable pulley 11 journaled at the upper end of an inclined standard 12 at the extreme bow of the vessel, the cable extending to any suitable drum or hoisting device and provided for the purpose of raising the drag when desired.

13 is a retaining member or rod pivotally connected at its forward end to the apex of the drag or catcher, its opposite end 65 being provided with a hook to engage an eye or opening 14 upon the bow of the vessel.

15, 15 are explosive mines anchored by means of anchor rods or cables 16. 70

In the drawings, I have shown a mine engaged by one of the hooks carried by the lower edge of the drag.

From the foregoing description, the operation of the device will be at once understood. The vessel provided with the mine drag or catcher is moved slowly through the mine field and the hooks carried by the lower end of the drag are thus brought into engagement with the cables connecting the mines with their anchors, the engagement of the hook being a short distance below the mine so that, when the mine is brought into contact with the drag or catcher, it encounters a yielding surface provided by the ropes forming the body of the catcher, thus avoiding contact with any fixed object which might cause the explosion of the mine. The mine thus engaged may, by releasing the hooked end of the rod 13 from the bow of the vessel and by drawing in of the cable 14, the drag with its mine attachment will be carried upward and transferred to the deck of the vessel, as will be readily understood.

95 What I claim to be new is:—
A triangular frame having a yielding

body portion, hooks disposed at intervals along the lower edge of the frame, supporting arms for the frame adapted to be pivotally connected at their inner ends to the 5 opposite sides of the bow of a vessel, means, as a stay rod, provided at its inner end with a hook to hold the drag in its operative position and by its disengagement with the vessel to permit the drag being raised to the

deck of the vessel, and a cable or other suitable device for raising the drag. 10

In testimony whereof I hereunto affix my signature in presence of two witnesses.

PETER ZAKIT.
